F. T. FEREDAY.

RAILWAY SIGNALING.

APPLICATION FILED DEC. 2, 1918.

1,348,101.

Patented July 27, 1920.

UNITED STATES PATENT OFFICE.

FREDERICK T. FEREDAY, OF ALBANY, NEW YORK, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,348,101.

Specification of Letters Patent.

Patented July 27, 1920.

Application filed December 2, 1918. Serial No. 264,910.

To all whom it may concern:

Be it known that I, FREDERICK T. FEREDAY, a citizen of the United States, residing at Albany, in the county of Albany and State of New York, have invented certain new and useful Improvements in Railway Signaling, of which the following is a specification.

My invention relates to railway signaling, and particularly to signaling of the type wherein a signal is controlled by a relay, which relay is in turn controlled by a circuit including a source of current.

One feature of my invention is the provision, in a system of the character set forth, of means operating when the signal reaches the "proceed" position to disconnect the relay from the circuit and connect such circuit directly with the signal, thereby saving the power ordinarily required to energize the relay while the signal indicates "proceed".

I will describe one form of signaling system embodying my invention, and will then point out the novel features thereof in claims.

The accompanying drawing is a view showing diagrammatically one form of signaling system embodying my invention.

Referring to the drawing, the reference characters 2, 2 designate the track rails of a railway track, which rails are divided by insulated joints 3 to form a plurality of successive block sections A—B, B—C, etc. Traffic along the track is normally in the direction indicated by the arrow. Each section is provided with a signal which is designated by the reference character S with an exponent corresponding to the location of the signal. Each of these signals comprises a semaphore 4, and is adapted to indicate "stop", "caution" or "proceed", according as the semaphore is in the horizontal, inclined or vertical position. The semaphore of each signal is biased to the horizontal or stop position by gravity, and is moved to the caution and proceed positions in opposition to the biasing force by an electric motor M; the semaphore is held in the position to which it has been so moved by a holding magnet H.

Adjacent to each signal is a battery or other suitable source of current, designated E with the same exponent as that of the cor-

responding signal, which battery at times supplies current to the signal for the operation and control thereof. The supply of current to each signal from its adjacent battery is controlled by a signal relay which is designated R with the same exponent as that of the corresponding signal. As here shown, each relay R is of the polarized type. The manner in which these relays are controlled will appear hereinafter.

The control of each signal S by the corresponding signal relay is in accordance with usual and well understood practice until the signal reaches the proceed position. When the signal relay is deenergized, the controlling circuits for the signal are opened so that the signal indicates "stop". For example, relay R^c is shown in the deenergized condition, so that signal S^c indicates "stop". Assume now that relay R^c becomes energized in such direction that its neutral contacts 5 and 6 are closed but its polar contact 7 is opened. The holding magnet H of signal S^c will then be energized through a circuit which passes from battery E^c, through wire 8, contact 5, wires 9 and 10, contact 11—12, wire 13, magnet H, wires 14 and 36, contact 6, wire 15 to battery E^c. Motor M will be energized at the same time by virtue of a circuit which passes from battery E^c through wire 8, contact 5, wires 9 and 16, contact 17—18, wire 19, motor M, wires 14 and 36, contact 6, wire 15 to battery E^c. The motor will, consequently, move the semaphore blade 4 to the inclined or caution position, at which point the motor will become deenergized due to the opening of contacts 17—18. This is the position in which signal S^b is shown in the drawing. If, now, referring to signal S^b, signal relay R^b becomes energized in the reverse direction, so that the polar contact 7 becomes closed, motor M will become energized by virtue of a circuit which passes from battery E^b, through wire 8, contacts 5 and 7, wires 20 and 21, contact 22—18, wire 19, motor M, wires 14 and 36, contact 6, and wire 15 to battery E^c. The semaphore blade will thus be moved to the vertical or proceed position, at which point the motor will be deenergized due to the opening of contact 22—18. During the movement of the signal between caution and proceed positions, the circuit for the holding magnet H is opened at contact

11—12, but prior to such opening a branch around this contact is closed, which branch passes from wire 21 through contact 23—12 to wire 13, so that the magnet continues to be energized until the signal reaches the proceed position.

- Each signal relay R is provided with a circuit which includes the source of current E adjacent the signal next in advance, and 10 a pole-changer P operated by the signal next in advance. Each such circuit is governed by a track circuit for the block section through which the corresponding signal governs traffic. Each track circuit comprises as usual a track battery b and a track relay designated by the reference character T with an exponent corresponding to that of the adjacent signal. Each pole changer P is reversed during the movement of the 20 corresponding signal between stop and caution positions. Each signal relay circuit is also controlled by a contact 28—29 operated by the adjacent signal which contact is closed at all times except when the signal 25 is in the proceed position. For example, the circuit for signal relay R^B is from battery E^C, through wire 24, pole-changer P, wires 25 and 26, relay R^B, wire 27, contact 28—29, contact 30 of track relay T^B, wire 31, pole changer P, wire 32 to battery E^C. When signal S^B reaches the proceed position, this circuit for relay R^B becomes open at contact 28—29, but the holding magnet H for signal S^B then becomes energized 35 from battery E^C, the circuit being from battery E^C, through wire 24, pole changer P, wires 25, 33 and 14, holding magnet H, wire 13, contact 12—23, wires 21 and 34, contact 35—29, contact 30, wire 31, pole 40 changer P and wire 32 to battery E^C. Signal S^A is shown in the proceed position, hence its holding magnet H is energized from battery E^B and relay R^A is deenergized.
- 45 Block section C—D being occupied by a car or train W, track relay T^C is deenergized so that holding magnet H is deenergized whereby signal S^C indicates stop. Track relay T^B is closed, hence the circuit for signal relay R^B is closed, but the pole-changer P operated by signal S^C is then in 50 such position that contact 7 of relay R^B is opened, whereby signal S^B indicates caution. The pole-changer P operated by this signal 55 S^B is now in the normal position so that relay R^A has been energized in such direction as to close contact 7. Signal S^A has, consequently, been moved to the proceed position. Just before reaching this position, the 60 circuit for relay R^A became opened at contact 28—29 and magnet H of signal S^A was connected with battery E^B, so that, as shown in the drawing, signal S^A is held in the proceed position due to current from battery E^B.

Assuming now that train W passes out of section C—D, track relay T^C will then become energized, whereupon relay R^C will become energized in such direction that its polarized contact 7 is open. Magnet H and 70 motor M will then be supplied with current from battery E^C, so that signal S^C will be moved to the caution position. When this position is reached, the circuit for motor M will become opened at contact 18, but the 75 circuit for magnet H will remain closed and this magnet will continue to receive current from battery E^C. Just before signal 80 reaches the caution position pole-changer P operated by this signal will reverse, thereby energizing relay R^B in such direction that contact 7 of this relay becomes closed. Motor M of signal S^B will then be supplied with current from battery E^B, so that this 85 signal will be moved to the proceed position. Just as this position is reached, contact 29—28 will open, thereby opening the circuit for relay R^B, but contact 29—35 will close, so that magnet H for signal S^B will 90 then be supplied with current from battery E^C. The parts associated with signal S^B will then be in the same positions as the parts associated with signal S^A.

I will next assume that with the parts as shown in the drawing, a train moving toward the right enters section A—B. The opening of track relay T^A opens the circuit for magnet H, so that signal S^A will move to the stop position. Contact 29 is shifted to contact 28 immediately after the semaphore blade 4 leaves the proceed position, but relay R^A remains deenergized because the circuit for this relay is then opened at contact 30 of track relay T^A, and so magnet H remains deenergized.

It will be seen from the foregoing that normally each signal is in the full proceed position, but that when a signal is in such position, the corresponding signal relay is deenergized, thus saving the energy which 110 has heretofore been necessary to keep this relay energized.

Although I have herein shown and described only one form of apparatus and circuits embodying my invention, it is understood that various changes and modifications may be made therein within the scope of the appended claims without departing from the spirit and scope of my invention.

Having thus described my invention, what 120 I claim is:

1. Apparatus of the type comprising a signal, a source of current, a signal relay for controlling the supply of current to said signal from said source, and a circuit for said relay including a second source of current, characterized by the combination therewith of means controlled by the signal and operating when the signal is in the proceed position for disconnecting said relay from 130

said second source of current and connecting said second source directly with the signal.

2. Apparatus of the type comprising a signal, a signal relay for controlling said signal, and a circuit for said relay including a source of current, characterized by the combination therewith of means controlled by said signal and operating when the signal is in proceed position to disconnect the relay 10 from its circuit and connect said circuit with the signal.

3. Apparatus of the type comprising a signal, a relay for controlling said signal, a circuit for said relay including circuit controlling means and a source of current, characterized by the combination therewith of means controlled by the signal and operating when the signal is in proceed position to disconnect said relay from said circuit 20 and place the signal under the immediate control of said circuit.

4. Apparatus of the type comprising a signal biased to stop position, a motor for moving it to a proceed position in opposition to the biasing force, holding means for holding the signal in such proceed position, a source of current for said motor and said holding means, a relay for controlling the supply of current to said motor and holding 25 means from said source, and a second source of current for energizing said relay, char- 30

acterized by the combination therewith of means controlled by said signal when the latter reaches such proceed position for disconnecting said second source of current 35 from said relay and connecting said second source with said holding means.

5. A signaling system of the type comprising a plurality of block sections, a signal for each section, a source of current for each signal, a signal relay for each signal for controlling the supply of current to such signal from the adjacent source, a circuit for each signal relay including the source of current adjacent to the signal next in advance, and track circuits for the block sections including track relays for controlling said signal relay circuits, characterized by the combination therewith of means controlled by each signal and operating when the signal is in 40 proceed position to disconnect the corresponding relay from its circuit and to connect the signal directly with such circuit whereby the signal then receives energy directly from the source of current adjacent 45 to the signal next in advance.

In testimony whereof I affix my signature in presence of two witnesses.

FREDERICK T. FEREDAY.
